UNITED STATES PATENT OFFICE.

HENRY H. KLINGBIEL, OF EL RENO, OKLAHOMA.

WRENCH.

1,263,435.

Specification of Letters Patent. Patented Apr. 23, 1918.

Application filed February 19, 1918. Serial No. 218,099.

To all whom it may concern:

Be it known that I, HENRY H. KLINGBIEL, a citizen of the United States, residing at El Reno, in the county of Canadian and 5 State of Oklahoma, have invented a new and useful Wrench, of which the following is a specification.

The device forming the subject matter of this application is a wrench adapted to be 10 used in inaccessible places, such as about the engine of an automobile, for loosening bolts and nuts, and one object of the invention is to provide a structure of the kind herein-after described, which will be well adapted 15 for use above set forth.

Another object of the invention is to provide novel means for mounting the sprocket wheels whereby motion is transmitted to the part which rotates the nut.

20 Another object of the invention is to provide a device of the class mentioned which will be strong and comprise few parts subject to deterioration or damage.

It is within the province of the disclosure 25 to improve generally and to enhance the utility of devices of that type to which the present invention appertains.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed can be made within the scope of what is claimed, without departing from the spirit of the invention.

In the accompanying drawings:—

Figure 1 shows in elevation, a device constructed in accordance with the invention;

Fig. 2 is a longitudinal section taken approximately on the line 2—2 of Fig. 1;

Fig. 3 is a section taken approximately on the line 3—3 of Fig. 1;

Fig. 4 is a section taken approximately on the line 4—4 of Fig. 1; and

Fig. 5 is an elevation showing one of the shafts.

The device forming the subject matter 50 of this application includes a body, made up of opposed side plates 1 and 2, held together and spaced apart by means of securing devices 3, connecting the side plates 1 and 2 intermediate their ends. A laterally 55 extended tubular sleeve 9 is threaded at 10 into the side plate 1 or is otherwise con-

nected therewith. The numeral 4 marks a tubular shaft having cylindrical ends 5. One of the ends 5 is journaled in the inner end of the sleeve 9 and the other of the 60 ends is journaled in the side plate 2, the shaft 4 embodying a polygonal hub 6 located between the side plates 1 and 2. The tubular shaft 4 has a polygonal bore 7. A

sprocket wheel 8 is mounted on the polygonal hub 6 and is held thereon against independent rotation, the sprocket wheel being located between the side plates 1 and 2, as clearly disclosed in Fig. 4. The numeral 11 marks an operating member journaled in the 70

sleeve 9 and substantially filling the same, so far as cross section is concerned, the sleeve coöperating with the operating member to afford increased strength. The operating member 11 embodies a laterally ex- 75

tended crank or loop 12, carrying a rotatable thrust head 14, the operating member, generally stated, resembling a bit stock. The operating member 11 terminates in a re- 80

duced, polygonal end 15, received against 85 rotation in the polygonal bore 7 of the shaft 4. The part 15 of the operating member 11 extends outwardly beyond the side plate 2 and carries a washer 16 and a cotter pin 17,

these elements coacting with the side plate 85 2 to prevent the operating member 11 from moving endwise in one direction. The operating member is prevented from moving endwise in an opposite direction, by reason of the fact that where the reduced end portion 15 of the operating member merges into 90

the body portion of the operating member, a shoulder 28 is formed, this shoulder 28 coacting with one end of the tubular shaft 4, and the tubular shaft 4 being prevented 95

from moving endwise, because the hub 6 of the shaft is received between the side plates 1 and 2, as shown in Fig. 4.

The invention comprises a shaft, denoted generally by the numeral 18, and embodying a reduced cylindrical end 19 journaled in the side plate 1, as shown in Fig. 3. The shaft 18 includes, further, a polygonal hub 20, located between the side plates 1 and 2, and a bearing portion 21 journaled in the 100 side plate 2. Projecting laterally from the bearing portion 21 of the shaft 18 is a head 22, shaped to receive a nut or other object which is to be rotated. The head 22 is of larger diameter than the bearing portion 21 105 of the shaft 18, and there is formed, therefore, a shoulder 23, which, coacting with

95

100

105

110

the outer face of the side plate 2, prevents the shaft 18 from moving in one direction. The shaft is prevented from moving in an opposite direction, longitudinally, by means 5 of a washer 24 and a cotter pin 25 carried by the end 19 of the shaft, these elements coacting with the outer face of the side plate 1. A sprocket wheel 26 is held on the polygonal hub 20 of the shaft 18 and is 10 disposed between the side plates 1 and 2. The sprocket wheels 8 and 26 are united by a chain 27.

In practical operation, when the member 15 11 is rotated by means of the crank 12, the tubular shaft 4 and consequently the sprocket wheel 8 will be rotated, motion being transmitted to the sprocket wheel 26 by way of the sprocket chain 27, the sprocket wheel 26 rotating the shaft 18 and rotation 20 being imparted to the head 22 which, being engaged with the nut or other object, will serve to loosen or tighten the same.

The device forming the subject matter of 25 this application is simple in construction and embodies few parts, the construction being such that the article can be built readily and be taken down for repair, should occasion demand.

Having thus described the invention, what 30 is claimed is:

1. In a device of the class described, a body comprising side plates; a laterally projecting sleeve carried by one side plate; a tubular shaft comprising an intermediate 35 polygonal hub located between the plates, an end journaled in the sleeve, and an end journaled in the other side plate, the shaft having a polygonal bore; an operating member journaled in the sleeve and having a polygonal end received in the bore; a sprocket wheel carried by the hub; a second shaft journaled in the body and provided 40

with nut engaging means; a sprocket wheel carried by the second shaft; and a sprocket chain connecting the sprocket wheels. 45

2. In a device of the class described, a body comprising side plates; a shaft including bearing portions journaled in the side plates, a hub between the bearing portions, and a head on one bearing portion, the head 50 embodying nut engaging means and defining a shoulder coacting with the outer face of one plate; securing means carried by the other bearing portion and coacting with the outer face of the other plate; a sprocket 55 wheel carried by the hub; a second shaft mounted for rotation in the body; a sprocket wheel carried by the second shaft; a chain connecting the sprocket wheels; and a laterally extended operating member interengaged with the second shaft. 60

3. In a device of the class described, a body made up of side plates; a laterally projecting sleeve carried by one side plate; an operating member mounted to rotate in the sleeve and comprising an angularly extended crank, the sleeve housing the operating member between the body and the crank; a sprocket wheel between the plates; means for connecting the sprocket wheel with the operating member; a shaft having nut engaging means disposed externally of the plates, the shaft being journaled in the plates; a sprocket wheel mounted on the shaft between the plates; and a chain connecting the sprocket wheels. 70 75

In testimony that I claim the foregoing as my own, I have hereto affixed my signature in the presence of two witnesses.

HENRY H. KLINGBIEL.
